ATTORNEY.

UNITED STATES PATENT OFFICE.

ROY CROSS, OF KANSAS CITY, MISSOURI.

PROCESS OF DESULPHURIZING AND PURIFYING PETROLEUM OIL.

Application filed November 21, 1923. Serial No. 676,028.

This invention relates to improvement in a process and apparatus for desulphurizing and purifying petroleum oil, and refers more particularly to a process in which oils are desulphurized, decolorized, purified, deodorized and sweetened by treatment with a solution of metal salts at temperatures and pressures best adapted to effect the most complete and efficient refining of the product treated.

Among the objects of the invention are to provide a process in which petroleum hydrocarbons, and particularly cracked distillates or oils containing objectionable amounts of sulphur compound, may be treated whereby the sulphur is removed and the oil sweetened and decolorized to produce a water-white product; to provide a process whereby the oil may be marketed directly after treatment, or when treating certain oils especially difficult to refine, an additional bleaching material may be used subsequent to the purifying treatment.

In the drawings:

The single figure is a diagrammatic side elevational view of the apparatus with parts shown in section.

While the apparatus, shown in the drawings, discloses a construction adaptable for the purpose described, it is understood that petroleum hydrocarbons may be treated by this process in other types of apparatus without departing from the spirit of the invention.

Referring briefly to the drawings, at 1 is shown a heating coil mounted in a furnace 2, preferably heated by means of gas burner 3. The discharge end of the heating coil communicates with a chamber 4, which has connection through a transfer line 5 to the treating tower 6. The treating tower in turn communicates through a line 7 with a bleaching tower or stage 8; this latter zone being connected by line 9 to a cooling coil 10. A receiving tank 11 is equipped with a liquid drawoff line 12, controlled by a valve 13.

Referring now to the method in which the oil is treated, the distillate or petroleum hydrocarbon which is to be treated is introduced to the system for purifying, desulphurizing, deodorizing and decolorizing. The hydrocarbon is supplied from any convenient source, not shown, through the pipe 1. This supply or charge is preferably continuously directed through the inlet line 14

and charged, by means of the pump 15, through the line 16 and thence through the heating oil 1 where it is heated to the desired treating temperature. The most efficient temperatures utilized will vary with the type of oil treated, but temperatures ranging from 200° to 500° F. will include a range which, normally, is sufficient to properly treat the oils by this process. At this temperature, there are sufficient volatile products evolved to generate a self-imposed pressure which is maintained upon the oil collecting in the chamber 4. If the vapors, evolved at the temperatures used, are insufficient to generate the desired pressure, an extraneous gas may be supplied through the pipe 17 controlled by a valve 18 or the pressure built up by the pump 15. The chamber is equipped with a pressure gauge 19 for ascertaining pressure maintained in the chamber.

A heated oil, under pressure, is discharged from the chamber through the line 5, controlled by a valve 20, and is conducted to the treating tower 6. A bypass line 21, controlled by a valve 22, is connected between the chamber and the line 5 beyond the valve 20.

The tower 6 consists preferably of a heavily insulated cylindrical chamber which has positioned therein a plurality of baffle members 23 which serve to cause the oil to follow a circuitous route in its travel from the bottom to the top of the tower. Between these baffle members is positioned a plurality of screens or metal lath, diagrammatically shown at 24, broken stone or other relatively inert material which has the ability of increasing the surface over which the oil is passed in order that a more complete treatment will be effected.

As described, the heated oil, under pressure, is introduced near the bottom of the tower and is caused to flow upward following the circuitous course permitted by the baffle members. At the same time, there is introduced to the top of the tower, through the line 25 regulated by a valve 26, a solution containing a metal salt or metal salts which flow downwardly through the tower in an opposed direction to the rising oil and, due to the screens or metal lath, these liquids are intimately combined in order that the treating material introduced to the top shall be brought in contact with as much of the oil as is possible in its travel. The treating

solution consists of certain metal salt such as lead, copper, antimony, zinc, manganese, or other metals which have the ability of combining with the sulphur, and other impurities, to remove it from the oil. These metal salts are dissolved in such solvents as water, alcohols, glycerin, ethylene-glycol, or other solvent materials which do not readily dissolve in the oil nor have the characteristics of dissolving any substantial amount of hydrocarbon material. The treating solutions which have been used with the most satisfactory results are sodium-plumbite solution known in the art as a doctor solution, and copper solution preferably in a neutral or weak acid condition.

It is well known that sodium plumbite solution has been used heretofore as a cold solution in treating oils to remove a part of their sulphur content, but it has never been satisfactorily demonstrated that such a solution can extract effectively sulphur from oils which have anything more than a very small amount of sulphur therein. This solution, when used under heat and pressure conditions such as those described, may be effectively utilized to treat the most odoriferous sulphur containing hydrocarbon products such as natural gasoline or cracked gasoline recovered from Luling crude, which is notoriously high in its sulphur content. The product resulting from this treatment was a water-white, clean, sweet distillate which could readily pass both a doctor and copper corrosion test. The oil, after treatment in the tower 6, passes over through the line 7 and may be withdrawn through the line 27 controlled by a valve 28, or if oil of a character which necessitates subsequent bleaching, the valve 28 may be closed and the valve 29 opened, whereupon the oil is introduced to a bleaching stage which consists of a tower 30 filled, between the upper and lower screens, with fuller's earth, bentonite, or other bleaching material. This latter container is preferably steam-jacketed, as shown at 32, for maintaining the proper heat during the bleaching treatment. The oil, on rising to the top of the container 3, flows off through the line 9, controlled by a valve 33, to a cooling coil 34 and is collected as refined distillate in the receiving tank 11 from which it may be drawn off as desired.

In place of the bleaching stage, the oil withdrawn from the line 27, if not sufficiently bleached, may be subsequently subjected to a dilute acid and caustic treatment in continuous agitators not shown but in practice well known in the art.

The treating substance, which is of heavier gravity than the oil, will find its way to the bottom of a treating tower 6 and may be drawn off through the line 35 regulated by a valve 36. This material may be settled out and regenerated for reuse or, if such

practice is ineffective to the satisfactory recovery of the material, it may simply be drawn off as waste.

As described, temperature range of from 200° to 500° F. results in the most satisfactory treatment; and pressures ranging from 25 to 150 pounds have proven to be satisfactory. The function of the pressure lies not only in the maintaining of the treating material or solution in the liquid phase, but also in the fact that it tends to combine more effectually and intimately the treating and treated material. The increase of temperature increases velocity of reaction amounting to doubling of the effectiveness for each 20° F. rise in temperature.

Normally, the hydrocarbons introduced from the chamber into the treating tower, is in a fluid state. A portion of the volatile hydrocarbons being in a vaporous condition, while a substantial portion of the oil being in a liquid state.

In the event that a regeneration of the treating material is not practical, it may be desirable to distill off the solvent material after such liquids as alcohol or glycerin is used. This recovered solvent may be subsequently recombined with a fresh supply of metal salts for reuse. Considerable reviving of the treated material may be effected by mechanical filtration to remove the objectionable impurities.

This treatment may also be used in cracking still towers for vapors under pressure or while the oil is in the vapor phase.

When treating benzine distillates where as subsequent distillation is necessary to recover a satisfactory marketable gasoline-like product, the cooling coil may be omitted and the treated material introduced while hot direct from the treating tower to a still or distilling means not shown.

I claim as my invention:

1. A process for refining, desulphurizing and purifying hydrocarbon distillate consisting in bringing the oil in intimate contact with a sodium plumbite solution at temperatures in excess of 200° F. by counterflowing the oil with the treating solution and maintaining sufficient pressure upon the treating stage to prevent substantial vaporization of the liquid materials.

2. A process for purifying and decolorizing hydrocarbon oils, comprising the steps of bringing the oil in intimate contact by counterflowing it with a sodium plumbite solution, the solvent being substantially immiscible in the oil, separating the oil and treating materials and subjecting the former to the bleaching action of an adsorptive agent and maintaining the oil at temperatures above 200° F. and under pressure sufficient to prevent substantial vaporization during operation.

ROY CROSS.
